MOVIE FILM VIEWER

Otto R. Nemeth, Santa Monica, Calif., assignor of one-third each to Anthony M. Frank, and Charles A. Palmer

Filed July 8, 1968, Ser. No. 12,652

Term of patent 14 years

Int. Cl. D16—04

U.S. Cl. D61—1

I claim:

The ornamental design for a movie film viewer, substantially as shown.
